UNITED STATES PATENT OFFICE.

JOSEPH F. MANGAN, OF ST. PAUL, MINNESOTA.

CHURN.

No. 813,563.

Specification of Letters Patent.

Patented Feb. 27, 1906.

Application filed February 6, 1905. Serial No. 244,252.

To all whom it may concern:

Be it known that I, JOSEPH F. MANGAN, a citizen of the United States, residing at St. Paul, in the county of Ramsey and State of Minnesota, have invented certain new and useful Improvements in Churns; and I do declare the following to be a full, clear, and exact description of the invention, such as will enable others skilled in the art to which it applies to make and use the same, reference being had to the accompanying drawings, and to the figures of reference marked thereon, which form a part of this specification.

This invention relates to improvements in churns, and has for its purpose to provide a cheap and handy churn by combining a simple churning mechanism with a common earthen jar, which is usually found in any household, but may also be furnished as a part of the complete churn, and which is very desirable for said purpose, because it is easy to keep clean and will give no objectionable taste to the butter. This and other objects I attain by the novel construction and arrangement of parts illustrated in the accompanying drawings, in which—

Figure 1 is a top view of the complete churn. Fig. 2 is a vertical section about as on the line *a a* in Fig. 1. Fig. 3 is a fractional view of the churn with a further improvement of the clamping mechanism holding the cover on the jar.

Referring to the drawings by reference-numerals, 1 designates a common cylindrical jar, which may hold two gallons or be of any other desired size. Upon said jar is placed a wooden cover 2, which is guided into a central position by guiding-studs 3, slipping inside the jar. Said cover is secured upon the jar by clamps 4, which in Figs. 1 and 2 are shown to consist of hooks beveled at 5, so as to be adapted to be forced more or less inward in under the flange 6 of the jar, while their upper arm 7 is flat and slotted for a thumb-screw 8, screwed into the wooden cover and having a shoulder 9, holding the arm 7 firmly in the adjusted position upon the cover. Upon the cover is secured a metallic frame 10, in which is journaled a horizontal shaft 11, having at one end the hand-crank 12 and on

the other end a bevel-gear 13, driving a bevel-pinion 14, fixed on the dasher-shaft 15, on the lower end of which is a socket 16, in which the pendant 17 of the dasher is firmly fixed, and thereby suspended above the bottom of the jar, so as not to need any bottom support, which would be difficult to provide in a jar. The wings 18 of the dasher are flat and secured with one end in the pendant 17, preferably in an oblique position, as shown at 18^x in Fig. 2; but they may also stand vertical.

In using the churn the cover 2 is simply removed while the cream is poured in. Then it is replaced and fastened and the crank is turned until the butter is formed, as may be observed through a lidded hole in the cover. (Not shown.) The cover is then removed and the dasher with it.

In Fig. 3 the clamp 4^b is so modified or improved that it will get a good hold, even if the flange 6 is small or considerably beveled at its under side. This is done by securing upon the cover 2 a small bracket 19, having slotted holes 20, in which trunnions 21 of the clamp are inserted. Upon the foot or projection 22 of the bracket presses the end of the thumb-screw 23, thereby drawing the lowest end of the clamp up under the flange 6 and at the same time crowding it inward against the jar, so that it cannot slip off from even a narrow and beveled flange like that indicated in said Fig. 3.

Having thus described the invention, what I claim, and desire to secure by Letters Patent, is—

1. The combination of an earthen jar having about its top an exterior rim, a cover on the jar, the bracket 19 secured upon the cover, a curved clamp having a vertically-playing pivot-joint in the bracket and its lower end engaging the under side of the rim, and in its upper end a thumb-screw pressing upon the cover so as to force the lower end of the clamp in and upward under the rim and lock it in that position.

2. The combination of an earthen jar having about its top an exterior rim, a cover on the jar, the bracket 19 secured upon the cover, a curved clamp having a vertically-playing pivot-joint in the bracket and its lower end

engaging the under side of the rim, and in
its upper end a thumb-screw pressing upon
the cover so as to force the lower end of the
clamp in and upward under the rim and lock
5 it in that position, and a hand-operated
churning mechanism carried by said cover
and operating within the jar.

In testimony whereof I affix my signature
in presence of two witnesses.

JOSEPH F. MANGAN.
